(57) **CLAIM**

The ornamental design for a garden sprinkler, as shown and described.

DESCRIPTION

FIG. 1 is a isometric view of my new garden sprinkler showing the new design;

FIG. 2 is a enlarged front to midpoint partial isometric view; FIG. 3 is a enlarged rear to midpoint partial isometric view thereof;

FIG. 4 is a enlarged top plan view of FIG. 2;

FIG. 5 is a enlarged top plan view of FIG. 3;

FIG. 6 is a enlarged right side elevation view of FIG. 2, the opposite side being a mirror image;

FIG. 7 is a enlarged right side elevation view of FIG. 3, the opposite side being a mirror image;

FIG. 8 is a enlarged front end elevation view of FIG. 1;

FIG. 9 is a enlarged rear end elevation view of FIG. 1;

FIG. 10 is a enlarged fragmentary isometric view of the apex portion of the front end of FIG. 1;

FIG. 11 is a enlarged fragmentary isometric view of the right side corner portion of the front end of FIG. 1, the opposite side being a mirror image;

FIG. 12 is a enlarged fragmentary isometric view of the apex portion of the rear end of FIG. 1; and,

FIG. 13 is a enlarged fragmentary isometric view of the right side corner portion of the rear end of FIG. 1, the opposite side being a mirror image.

The portions that would indicate height and length relationships in all Figs. except FIGS. 6-9 are shown fragmented to show their indeterminateness in height and length.
